UNITED STATES PATENT OFFICE.

LE ROY J. THOMPSON, OF GRAND RAPIDS, MICHIGAN.

DISPENSING-TANK STRUCTURE.

Application filed March 10, 1928. Serial No. 260,702.

This invention relates to safety devices for dispensing tank structures.

The objects of the invention are:

First, to provide an improved dispensing tank with safety dispensing faucet structure that is simple in operation and automatic in action.

Second, to provide an improved dispensing tank for explosive fluid with safeguard means to prevent the accidental filling of such a gasoline dispensing tank with kerosene and to prevent the accidental dispensing of gasoline from the tank or the accidental filling and dispensing of an explosive fluid for one that is merely combustible.

Third, to provide such a tank that can be readily adjusted for gasoline or kerosene and control both the filling and the dispensing to avoid accidents.

Fourth, to provide such a tank with an improved valve mechanism from which fluid can only be drawn and discharged into containers used for the particular fluid.

Objects pertaining to details and economies of construction and operation will definitely appear from the description to follow. The invention is defined in the claims.

A structure embodying in a preferred form the features of my invention is clearly illustrated in the accompanying drawing, in which:

Fig. 1 is a perspective view of a truck tank with three compartments, the dispensing faucet for one compartment being shown in full lines and the system of pipes for all in dotted lines, two dispensing valves being omitted.

Fig. 2 is a side perspective view of my improved safeguard mechanism and connections to the tank detached, taken from the right hand side of the center faucet mechanism of Fig. 1, parts being in section or broken to show details.

Fig. 3 is an enlarged side elevation view of the faucet and connections from the left hand side of Fig. 1, a gasoline can being shown in dotted lines.

Fig. 4 is an enlarged partial vertical longitudinal sectional view of the faucet taken on line corresponding to line 4—4 of Fig. 7, the valve lever and a kerosene can being shown by dotted lines.

Fig. 5 is an enlarged partial vertical longitudinal sectional elevation view taken on line 5—5 of Fig. 9 showing the fluid outlet

connection from the tank and the safety control connecting mechanism shown in full lines.

Fig. 6 is an enlarged elevation view of the safety connection and the slotted tube for adjustment of said mechanism. 60

Fig. 7 is an enlarged sectional view of the dispensing faucet taken on inclined line 7—7 of Fig. 4, parts of the locking mechanism being shown in full lines. 65

Fig. 8 is a detail sectional view on right angle line 8—8 of Figs. 1, 10, and 12 of the filler opening flange and plate shutter on the tank.

Fig. 8A is a detail view of the hub 8 showing screw holes for adjustment. 70

Fig. 9 is an enlarged detail sectional view on line 9—9 of Fig. 5, the angular adjustment of the pipe being shown by dotted lines. 75

Fig. 10 is a plan view of the filler shutter disk with the opening in alinement for gasoline, the angular adjustment holes being shown by dotted lines.

Fig. 10A is a plan view of the cross nozzle that is used for filling with gasoline. 80

Fig. 11 is a plan view of the filler shutter disk with the opening in alinement for kerosene.

Fig. 11A is a plan view of the nozzle used for kerosene. 85

Fig. 12 is a plan view of the screw threaded shutter plate having port therein set for the gasoline filler nozzle.

Fig. 13 is a partial plan elevation view of the nozzle with a hose coupling attached to the dispensing cock. 90

My invention applies particularly to dispensing tank wagons, especially those having compartments for dispensing gasoline, kerosene and the like. The structure illustrated applies to such a tank having three compartments, all of which are identical except in the matter of deflecting the delivery pipes so that the delivery faucets can be disposed side by side at the end of the tank which in use is the rear of the truck. 95

It will be readily understood that very serious consequences may follow from the accidental delivery of gasoline, an explosive fluid, in place of kerosene, which is merely combustible. Many scores of lives are lost each year by the accidents which follow such mistakes in delivery. It is important to avoid such accidents. 100 105 110

In the dispensing of these products it is quite desirable to have different grades of both gasoline and kerosene carried in different compartments of the same tank, and it is of the utmost importance to insure that an explosive fluid, gasoline, will not be delivered in place of one that is merely combustible. It is only less important that the merely combustible fluid be not delivered by mistake. 10 The annoyance and waste caused by delivery of kerosene for gasoline is obvious.

I have therefore provided a construction of tank with delivery faucets with safety devices that are designed to prevent the suspension of a gasoline container on the faucet unless gasoline is to be delivered, and also provide in connection with that safety adjustment, connections and mechanism to a shutter control for the intake or filler opening of the tank compartment and a connection therebetween so that when one is adjusted the other will be correspondingly adjusted, and, consequently, when the dispensing faucet shows that gasoline may be drawn, 20 the intake or filler shutter to the compartment is adjusted and opened for gasoline and closed to kerosene, and vice versa, and is closed and shut off until adjusted to correspond to the set of the safety device. 25 30 The parts will be identified by their numerals of reference which are the same in all views.

1 is a truck tank having three compartments for explosive and combustible fluid such as gasoline or kerosene. The compartments and faucet structure and safety devices for each are the same so only one will be detailed and described.

2 is the flanged filler opening, screw threaded inside, of the usual construction. 3 is the usual screw threaded cover of the filler opening. 4 is the dispensing faucet having upper suspending hook 25 for a gasoline can and lower hook 27 for a kerosene can. 5 is the pipe connection from the under side of the tank to the dispensing faucet which is provided with angle connections if necessary. 6 is the interlocking shutter means to prevent accidental filling of the wrong fluid and is cooperatively connected to the dispensing faucet safety indicators and locks.

The interlocking shutter means consists of the adjustable screw-threaded apertured shutter disk 61 screw threaded in the flanged opening 2 having a screw stop 63 to prevent the turning of the disk through the opening of the tank. 62 is an elongated opening in the disk 61. The gasoline nozzle is flanged and extends at right angles to the filler pipe and the disk 61 should be adjusted to correspond, see Figs. 10 and 10A. The kerosene nozzle is straight in relation to the filler pipe and the plate 61 should be turned ninety degrees as seen in Figs. 11 and 11A. The wrong nozzle thus cannot be introduced to fill the

tank. The determining factor for the position of opening 62 and as to which the nozzle is to be used, is the position of the opening 71 in the disk shutter 7.

The disk shutter 7 has a filler opening 71 adapted to register with opening 62 and is controlled from the faucet. 8 is a hub for the pivoted disk shutter and 81 is a shouldered pivot screw threaded into the disk 61. The angular adjustment of the shutter disk is maintained by the screw 82 in one of the holes 84. These holes are on the same angle as the angle of the delivery pipes on the bottom of the tank. The disk shutter 7 is connected to the locking means for the dispensing faucet by shaft and gear connections so that when the dispensing faucet is set for gasoline the disk shutter 71 will be set for gasoline.

9 is a universal joint carried by the hub 8. 10 is a connecting shaft. 11 is a universal joint connecting the upright shaft 10 to the sliding extension shaft 131 of the adjusting gear of the interlocking means. 12 is the pipe flange connection from the tank to the pipe T 121. 122 is a plug inserted at the bottom connection of the T. 123 is a supporting post carried by plug 122.

13 is a beveled gear journaled on the top of the post 123 and carrying the sliding extension shaft 131. A key 132 is provided for slidably operating in the key-way 111 of the lower extension 112 of the universal joint. 133 is a transverse slot in the gear hub to cooperate with the stop pin 124 in the post 123. This controls to a quarter turn which is all the movement required.

14 is the delivery pipe connection to the faucet 4 connected by flange 141 to a flange 142 on the dispensing faucet.

15 is a connecting shaft having a sliding joint with key 151 for longitudinal adjustment and connection to the control means. 152 is a flexible shaft connection between the rod 15 and the beveled gear 16 for use when the pipe is bent.

The beveled gear 16 is journaled at 17 on cross pin 171 carried by the post 123.

The dispensing faucet mechanism comprises a hand lever 18 shown by dotted lines in Fig. 4 mounted on the squared shank 183 of the valve operating rockshaft 180. 182 is a rocker arm on shaft 180 coacting with a disk lift valve 19 of a well-known type. 191 is the valve seat. 192 is the valve stem coacting with the rocker arm 182 of the operating lever. 193 are projecting lugs on the valve to guide and centrally locate the same. 194 is a bifurcated projecting valve stem carrying the compression spring 20. 41 is a cap with guiding socket 42 for said valve stem.

21 is a locking pin screw threaded for adjustment in the extension 195 of the valve stem 194. 211 is a reduced portion on the locking pin to engage the slots 212. 22 is the horizontal locking shaft having a tubular ex-

tension 221 slotted at 222 to coact with key 151 on rod 15.

23 is the outer bearing for the rod. 231 is the stuffing box therefor. 24 is a hub therefor pinned to the locking shaft. 241 is a projecting handle for locking the suspending hook 25 out of use. 242 is an arm on said hub 24 projecting at right angles to the arm 241 to lock or block the second suspending hook 27 when it is not to be used.

25 is the hook provided on the faucet for the gasoline can 26 as shown by dotted lines in Fig. 3, the bail 261 being elongated and of a greater length than the bail on the kerosene can. The can tops are provided with guards and must be at the right height to receive the fluid being dispensed.

27 is the hook on the faucet for the bail 28 of the kerosene can 281. 29 is a stop for the hand lever of the valve, holding the valve in open position. 30 are the angular pipe connections in the delivery pipe.

An additional locking means is provided whereby the hose coupling 31 screw threaded on the end of the discharge faucet abuts the lower end of the locking slide 311 slotted at 312 to receive the retaining screw 313. It must be understood here that unless arm 242 is closed tight against hook 27, or arm 241 against hook 25, the faucet cannot be closed because the pin 211 cannot drop into the recess 212 to permit the closing. Thus when the hose is connected it is only possible to deliver through the hose, and consequently no other manipulation is possible, and in this position there is protection from any fluid being introduced into the tank that is not intended to be drawn off. It must also be understood that the hooks 25 and 27 can have nothing hung on them and that there can be no hose on the faucet. Also, the faucet must be opened to change the adjustment to permit the entry of a different fluid than that which the tank last contained.

32 is a filling nozzle for gasoline or the like. 33 is a straight filling nozzle for kerosene or the like.

When the devices are installed on the tank the pipes on each side of the center pipe have connections 30 at an angle from the outlet on the tank. In each case adjustment of the safety device is necessary; otherwise it would throw the valve disk 7 with opening 71 out of proper alignment with the filler nozzle shown in Figs. 10A and 11A. These openings must be in proper alignment with the filler nozzle to get the material in the tank.

To compensate for either the right or left throw of the pipe 14, as shown on the dotted lines 30 in Figs. 1 and 9, and to aline the filler with opening 71 properly, a series of screw holes 84 in the hub 8 are provided, see Fig. 8A.

With the parts thus arranged the tank is ready for filling with the particular fluid for which the discharge faucet 4 is set. My im-

proved structure prevents the use of any other container than that for which the discharge faucet is set. For this I provide bails of different lengths. The bail of the gasoline container is of the greater length which insures the using of the proper hook.

When the hook 27 is locked it is impossible to hook the can with the short bail to the hook 25, the distance from the end of the discharge nozzle to the hook being too great. The longer bail 261 can be hooked in the hook 27 used for the kerosene container but by using this hook the end of the nozzle would be above the splash guard of the container, thereby spilling the contents over the bucket and on the ground, which indicates the wrong product is being withdrawn.

A change in the adjustment can only be made when there is no container on either hook and, also, when no hose connection is made, and upon opening valve 19. If the tank contains any fluid it will be spilled on the ground, which indicates the tank has not been emptied, and that an adjustment for a fluid of a different nature should not be made. Under such conditions wrong adjustment would not be done by accident.

All of these operations tend to act as a means for preventing the operator of the truck from vending a fluid that is of an explosive nature for an ordinary combustible fluid or vice versa. The very dangerous and often fatal accidents resulting from the delivery of gasoline are avoided. The waste and annoyance of delivering kerosene by mistake are obviated.

Having thus described my invention what I claim as new and desire to secure by Letters Patent is:

1. The combination in a dispensing tank of an internally screw threaded flanged intake opening, an adjustable screw threaded shutter disk with elongated intake aperture at one side of the center disposed in the said opening, a pivoted shutter disk with aperture corresponding to that on the adjustable disk and adapted to open and close the shutter disk, a dispensing faucet for the said tank provided with a plurality of suspension hooks for supporting containers, a valve in said faucet having a lock pin, a rock shaft with longitudinal notches to be engaged by said pin, lock fingers on the rock shaft positioned to selectively obstruct and lock corresponding suspension hooks, a connection from the said rock shaft to the pivoted shutter disk at the intake opening whereby the disk is shifted to the corresponding position of the lock fingers, said connection comprising a hub carried by said pivoted disk, an upright shaft with slip joint and universal joints, miter gears between said upright shaft and said rock shaft, a post with journal pin for supporting the gear that is operatively connected to said disk.

2. The combination of a dispensing tank of an internally screw threaded flanged intake opening, an adjustable screw threaded shutter disk with elongated intake aperture at one side of the center disposed in the said opening, a pivoted shutter disk with aperture corresponding to that on the adjustable disk and adapted to open and close the shutter disk, a dispensing faucet for the said tank provided with a plurality of suspension hooks for supporting containers, a valve in said faucet having a lock pin, a rock shaft with longitudinal notches to be engaged by said pin, a connection from the said rock shaft to the pivoted shutter disk at the intake opening whereby the disk is controlled.

3. The combination in a dispensing tank of a flanged intake opening, an adjustable shutter disk with elongated intake aperture at one side of the center disposed in the said opening, a pivoted shutter disk with aperture corresponding to that on the adjustable disk and adapted to open and close the shutter disk, a dispensing faucet for the said tank provided with a plurality of suspension hooks for supporting containers, a valve in said faucet having a lock pin, a rock shaft with longitudinal notches to be engaged by said pin, lock fingers on the rock shaft positioned to selectively obstruct and lock corresponding suspension hooks, a connection from the said rock shaft to the pivoted shutter disk at the intake opening whereby the disk is shifted to the corresponding position of the lock fingers, said connection comprising a hub carried by said pivoted disk, an upright shaft with slip joint and universal joints, miter gears between said upright shaft and said rock shaft, a post with journal pin for supporting the gear that is operatively connected to said disk.

4. The combination in a dispensing tank of a flanged intake opening, an adjustable shutter disk with elongated intake aperture at one side of the center disposed in the said opening, a pivoted shutter disk with aperture corresponding to that on the adjustable disk and adapted to open and close the shutter disk, a dispensing faucet for the said tank provided with a plurality of suspension hooks for supporting containers, a valve in said faucet having a lock pin, a rock shaft with longitudinal notches to be engaged by said pin, safety devices to control said hooks actuated by said rock shaft, a connection from the said rock shaft to the pivoted shutter disk at the intake opening whereby the disk is controlled.

5. The combination in a dispensing tank of a flanged intake opening, an adjustable shutter disk with elongated intake aperture at one side of the center disposed in the said opening, a pivoted shutter disk with aperture corresponding to that on the adjustable disk and adapted to open and close the shutter disk, a dispensing faucet for the said tank provided with a plurality of suspension hooks for sup-

porting containers, a valve in said faucet having a lock pin, a rock shaft with longitudinal notches to be engaged by said pin, lock fingers on the rock shaft positioned to selectively obstruct and lock corresponding suspension hooks, a connection from the said rock shaft to the pivoted shutter disk at the intake opening whereby the disk is shifted to the corresponding position of the safety device.

6. The combination in a dispensing tank of an internally screw threaded flanged intake opening, an adjustable screw threaded shutter disk with elongated intake aperture at one side of the center disposed in the said opening, a pivoted shutter disk with aperture corresponding to that on the adjustable disk and adapted to open and close the shutter disk, a dispensing faucet for the said tank provided with adjustable indicator control means for said faucet and a connection from the said indicator means to the pivoted shutter disk at the intake opening whereby the disk is shifted to the corresponding position of the safety device.

7. A safety faucet for dispensing tanks comprising a valve, a casing with a plurality of suspension hooks for containers at different elevations, pivoted safety guard indicator devices to cooperate with said hooks, locking means with connections for locking engagement with the valve adjustable to selectively bar the use of said hooks and to be operative to adjust said locking means only when the valve is open.

8. A safety dispensing faucet device for use with a dispensing tank comprising, a casing with a plurality of hooks, a spring pressed valve within the casing with a lock pin thereon, guards for obstructing selectively the said hooks with a notched means cooperating with the pin on the valve to lock same in position when the valve is closed.

9. A tank supplied with a dispensing faucet screw threaded for hose connection, hooks on the faucet for dispensing containers, guards therefor, a slide with lock projection positioned to be operated by the attaching of a hose coupling to force the same into locking engagement with the said guards and retain the same in locked position, preventing the use of the hooks until the hose is disconnected thereby preventing a shifting of the guard device while the dispensing hose is in position.

10. In a dispensing tank the combination of a flanged intake opening for receiving the cover, an adjustable shutter plate with opening at one side of the center disposed in the intake opening to indicate by position the fluid required, a pivoted shutter plate with opening corresponding to that in the adjustable shutter plate and safety adjustable guard arm devices with connections to the pivoted shutter plate to close the shutter to prevent the filling of the tank with other than the re-

quired fluid indicated by the adjustment of the shutter plate.

11. The combination of a dispensing tank, an intake therefor with adjustable shutter 5 with opening at one side of the center, a pivoted shutter plate with corresponding opening, a delivery faucet, adjustable safety guard arm device at the delivery faucet with indicators for its use and connections from said 10 safety device to the pivoted shutter to control the same to the required delivery positions, thereby closing the adjustable shutter until

set to the required position, to insure the co-ordination of the filling and dispensing means.

12. The combination of a dispensing tank, an intake therefor with a shutter, a delivery faucet, safety indicator guard arm devices at the delivery faucet, connection therefrom to the shutter to control the same. 15 20

In witness whereof I have hereunto set my hand.

LE ROY J. THOMPSON.
